Primary Examiner — Susan E Krakower

Assistant Examiner — Jerry Shiuan-Hua Hsu

CLAIM

The ornamental design for a pedal, as shown and described.

DESCRIPTION

FIG. 1 is a front, left side perspective view of a pedal, showing my new design;

FIG. 2 is a rear, right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof, shown enlarged for ease of illustration;

FIG. 8 is a bottom view thereof, shown enlarged for ease of illustration;

FIG. 9 is a front, right side perspective view thereof, shown in a second configuration; and,

FIG. 10 is a rear, left side perspective view thereof, shown in a second configuration.

The broken lines in the drawings illustrate the portions of the pedal, which form no part of the claimed design.

1 Claim, 10 Drawing Sheets
